(57) **CLAIM**

The ornamental design for an autoinjector housing, as shown and described.

DESCRIPTION

FIG. 1 is a front top right perspective view of an autoinjector housing showing our new design;

FIG. 2 is a front bottom left perspective view thereof;

FIG. 3 is a rear elevation view thereof, the front elevation view being a mirror image thereof;

FIG. 4 is a right side view thereof;

FIG. 5 is a left side view thereof;

FIG. 6 is a top plan view thereof; and,

FIG. 7 is a bottom plan view thereof.

The broken lines of even length shown in the drawings illustrate portions of the autoinjector housing that forms no part of the claimed design.
